DESIGN FOR A LAST

Fred W. Stuart, Beverly, Mass.

Application December 26, 1935, Serial No. 60,280

Term of patent 3½ years

To whom it may concern:

Be it known that I, Fred W. Stuart, a citizen of the United States and a resident of Beverly, in the county of Essex and Commonwealth of Massachusetts, have invented a new, original, and ornamental Design for a Last, of which the following is a specification, reference being had to the accompanying drawing, forming a part thereof, in which

Fig. 1 is a plan view of a last showing my design;

Fig. 2 is a view in side elevation,

Fig. 3 is a view in perspective, and
Fig. 4 is a view in cross section on the line 4—4
of Fig. 2.

The dominant feature of my design resides in the faceted effect imparted to the toe end of a last by substantially straight side walls, a central ridge and an angular end edge line.

I claim:

The ornamental design for a last substantially as shown and described.

FRED W. STUART.
